United States Patent Office

Des. 181,798
Patented Dec. 24, 1957

181,798

COVER FOR SAUCE PAN OR OTHER KITCHEN UTENSIL

Richard F. Krause, Massillon, Ohio, assignor to The Enterprise Aluminum Company, Massillon, Ohio, a corporation of Ohio

Application May 7, 1957, Serial No. 46,041

Term of patent 7 years

(Cl. D44—1)

Fig. 1

Fig. 3

Fig. 1 is a top plan view of a cover for sauce pan or other kitchen utensil showing my new design;

Fig. 2 is a side elevation of the same; and

Fig. 3 is a fragmentary sectional view taken substantially on the line 3—3, Fig. 1.

I claim:

The ornamental design for a cover for sauce pan or other kitchen utensil, substantially as shown.
